UNITED STATES PATENT OFFICE

JOHN L. KOUBEK, OF ANDERSON, INDIANA, ASSIGNOR TO GUIDE LAMP CORPORATION,
OF ANDERSON, INDIANA, A CORPORATION OF DELAWARE

AUXILIARY DRIVING LIGHT

Application filed May 9, 1931. Serial No. 536,177.

This invention has to do particularly with a lamp designed to throw light to the far sides of an automobile to light the way in turning corners and to give better illumination in case of fog. The lamp is intended for use in conjunction with the headlamps regularly used on automobiles. Conventional headlamps project most of their light down the road, with a smaller proportion directed to the sides of the road and to the foreground for general illumination. As a consequence, when the car is turned, an insufficient quantity of light or none at all is projected in the direction in which the turn is being made.

My improved lamp is preferably so designed that while its beams slightly overlap the beams from the headlamps, the greater proportion of the light is directed to the extreme sides of the roadway to which the headlamp rays are not directed. The light from my lamp not only permits turns to be made with convenience and safety, but by turning off the main headlamps, and turning on my improved auxiliary lamp, very good fog lighting is obtained. The sidewise directed beams from my lamp illuminate the way much better in fog than do the forwardly directed headlamp beams for less of the light is reflected from the suspended particles of water vapor into the eyes of the driver.

My improved lamp is characterized by absence of moving parts, and consists in its preferred form of a simple parabolic reflector, an incandescent lamp with a filament at the focus of the reflector, and a lens of special design for directing the light into two laterally spaced beams with a dark space between them, this space being normally filled in with light from the headlamps. As the auxiliary lighting will be most useful in turning corners I have preferably arranged my lamp in a special lighting circuit containing a switch operated by turning the steering gear of the car so that when the front wheels of the car have been turned through a predetermined angle the auxiliary lamp is turned on to project its beams at the extreme sides of the road affording illumination for either direction of turn.

The lens may be of any one of a number of

designs, and in general is characterized by the provision of a combination of vertical flutes and vertical prisms for giving the desired lateral spread to the light. In some forms of my invention the prisms and flutes are formed on opposite sides of the lens, while in other forms they are combined on one face of the lens, leaving the outer face a plain surface which may be readily cleaned.

The preferred design of lens is provided with vertical prisms on one face and superimposed vertical concave flutes on the other face. By varying the angle of the prisms, the radius of the flutes and the thickness of the glass, the divergence of the beams and their lateral spread may be very readily controlled. If desired the lens may be provided with horizontal prisms to vary the depth of the beam.

I have particularly emphasized the value of my lamp for use as an auxiliary lamp on automobiles. However, fundamentally, the design produces two long, narrow and more or less widely separated beams. Lighting apparatus having these characteristics is likewise useful for roadway illumination, for aeroplane landing field beacons, and kindred service, and it is to be understood that all such uses come within the scope of my invention, whether the lamp be arranged so that its beams are projected in a horizontal plane or in a vertical plane, or any other.

In the drawings:

Figure 1 is a front view of a lamp embodying my invention.

Figure 2 is a vertical section, showing by light rays, and in an exaggerated manner, the effect of the horizontal prisms on vertical distribution of light.

Figure 3 is a horizontal section showing diagrammatically the horizontal distribution of light but at a point nearer the car than that normally used in determining light distribution.

Figure 4 is an enlarged horizontal section through a portion of the lens showing the action of the lens on representative rays.

Figure 5 is a wiring diagram showing how the invention will be applied on an automobile.

Figure 6 is a horizontal section corresponding to Figure 3 but showing the bulb equipped with a cap.

Figure 7 is a perspective view of the cap shown in Figure 6.

Figures 8 to 13 are horizontal sections through modified forms of lens.

The construction of the lamp is conventional except for the lens although it is the combination of lens, reflector and light source that produces the desired illumination.

Referring now to the preferred construction shown in Figures 1 to 4, the lamp consists of a housing 10, containing a plain parabolic reflector 12, covered by my improved lens 14, held on by lens retaining ring 16. The lens ring may be secured to the housing in any suitable manner. The reflector is equipped with a bulb 24 having its filament 26 at the focus of the reflector.

The construction of the lens is best illustrated in Figure 4, which is a horizontal section through a portion of it. On the side nearer the light source, the lens is provided with vertical prisms 28, while on the opposite side it is provided with relatively shallow vertical flutes 30, coextensive with the prisms. Both the prisms and flutes are symmetrical with respect to planes normal to the plane of the lens and joining the apices of the prisms with the centers of curvature of the flutes.

In the design illustrated the prisms have 70° angles, and the radius of the flutes is $\frac{3}{8}$ ". The minimum thickness of the lens is $\frac{1}{8}$ ".

I have found these proportions to be most advantageous for use on auxiliary lights for automobiles. The advantages of these proportions will be apparent by tracing the ray which I have marked A on Figure 4. This

ray strikes one of the prisms near its apex, and at an angle B of about 55 degrees, as shown. With this angle, the loss of light by reflection at the surface of the glass is about 7½%. If the angle is increased the loss increases so rapidly as to render the design so inefficient as to be commercially impractical. In other words, this angle is so chosen that the loss of light by reflection is the maximum permissible from commercial considerations.

Following the beam through the glass it strikes the surface of the flute 30 and is deflected sharply to the left. The angle of incidence C is about 37°. With this angle, the loss of light by reflection within the glass is about 12%. As the angle is increased, this loss increases. Thus at 39½° the loss is 18%. At 41° 49' the loss becomes 100%. For certain designs where the amount of light at the extreme spread of the beam is not an important factor, it might be permissible to go to 39½°. Beyond this the loss increases so rapidly as to render the design so inefficient as to be impractical. Like the angle of incidence at the prisms 28, this angle is so chosen

that the loss of light by internal reflection is the maximum permissible.

Now the angle C is determined not only by the radius of curvature of the flute 28, but also by the thickness of the lens. If the lens thickness be increased materially the ray A will emerge from the surface of the next flute and will be bent in the opposite direction to that desired. If the lens thickness be materially decreased the ray A will emerge from the surface of the flute nearer its axis of symmetry and will consequently not be deflected to the left to the full amount desired. The conditions specified are optimum conditions.

By studying the other rays it will be noted that the rays are spread laterally by the action of the flutes, and that each prism and flute directs a fan shaped beam of light to the left and another fan shaped beam of light to the right. The corresponding composite beam patterns are shown on Figure 3. The center is dark, except possibly for a very slight amount of light diffused by the rays striking the extreme tips of the prisms or the extreme depths of the troughs between them. In commercial production of lenses by pressing, it is not possible to accurately shape these portions into sharp angles so they have been rounded off and the light striking them is diffused.

To vary the depth of the beam I have preferably provided prisms at top and bottom as indicated in Figure 2. The upper prism 32, is preferably a 4° prism, and the lower prism 34 is a 2° prism. This gives a desirable vertical distribution with the lamp mounted between the two headlamps and slightly below their axes.

The wiring diagram is self-explanatory.

The headlamps 39 are supplied with current from battery 40 through the ammeter and the usual operator controlled switch 42. The auxiliary lamp 10 is connected with the battery circuit beyond the ammeter and its circuit is controlled by switch 44 of any suitable construction connected to a part of the steering gear, for example the pitman arm. When the steering gear is turned through a predetermined angle, depending upon the adjustment of the switch, the auxiliary lamp 10 is turned on illuminating the far sides of the road. The auxiliary lamp is also provided with a separate connection to the battery in any suitable manner, for example, through the battery terminal on the dash ammeter. This connection is controlled by a separate switch 46 so that if desired the lamp may be used when going straight ahead through fog, the headlamps in such case being turned off, and the cowl lamps 48 being used as markers.

The construction is susceptible of some modification in practice. For example, the prisms may be made slightly convex or concave, if desired, to give a certain amount of

additional lateral spread. As previously pointed out, the spread of the beam may also be varied by changing the radius of curvature of the flutes, but owing to the symmetry of 5 the design the light will be evenly distributed throughout the beams.

The angles of the prisms may be varied to control the degree of divergence of the beams. 60° is the limit for maximum divergence for 10 a lesser angle prism results in so much loss by reflection as to be impractical.

In Figure 6, I have illustrated the lamp shown in Figure 3 with the bulb provided with a fog cap 36. This cap is illustrated 15 also in Figure 7. As indicated by the dotted line in Figure 6 the cap will cut off all direct rays issuing from the filament. The only light issuing from the lamp will then be the light striking the reflector and redirected 20 by the lens. As shown in Figure 3 this light is projected to opposite sides of the road. With this arrangement no light of any sort is directed forwardly. It is the forwardly directed light that is reflected by the particles 25 of moisture in the air in foggy weather, making it impossible to see ahead. By eliminating the forwardly directed light, very good fog illumination is obtained from the sidewise directed beams.

30 In Figure 8, I have illustrated a modified form of lens. This form differs from the form shown in Figure 4 in that the prisms 28' are truncated, as indicated at 38 so that some of the rays will pass through the lens 35 without appreciable change in direction. This lens will not give as satisfactory illumination under fog conditions, but will illuminate the full width of the road should this be desired.

40 The lens shown in Figure 9 differs from the lens of Figure 4 in that I have employed convex flutes as at 40 instead of concave flutes.

As shown in Figure 10, the lens shown in 45 Figure 9 may be modified by truncating the prisms, as shown at 42.

In Figure 11, I have shown a modification in which the outer face 44 of the lens is plain, and the inner face is provided with a configuration 50 resulting from the combination of flutes and prisms. I have indicated one of the vertical prisms built into this form of design by the dotted lines 45. This prism may be resolved into two right triangles having 55 their bases 46 in alignment, and their hypotenuses 48 at an angle to each other as shown. The glass between the hypotenuse and the inner surface 50 of the lens is a con-

ventional flute. This design has the advantage that the outer face of the lens may be plain, and, therefore, easily cleaned.

The construction of Figure 12 is the same as that of Figure 11 except that convex flutes 70 are employed. In this figure I have indicated the built-in prisms by the same reference characters as in Figure 11. Obviously the construction shown in Figures 11 and 12 may be truncated as in the case of Figures 8 and 10, if it is desired to project some light forwardly. 75

I have also modified the design of lens shown in Figure 4 in the following manner with successful results. Thus instead of 80 employing 70° prisms I have made use of 90° prisms, and instead of using flutes of $\frac{3}{8}$ " radius, I have employed flutes having a radius of $\frac{3}{2}$ ". I have shown this design in 85 Figure 13, and this figure likewise illustrates at 60 the flattening of the ridge between the flutes. The purpose of this is to allow the light to bend to the extreme angle, and to facilitate manufacture by reducing the depth 90 of the flutes. Were the flutes not flattened off at 60, the rays forming the extreme boundaries of the beam would strike the sides of the ridges and be reflected toward the center of the road. This will be made clear by 95 tracing the beam R on the drawings. This beam is shown deflected as at R' upon striking the dotted line extension 62 of the ridge between the flutes. With the described design I employ a 37½° angle of incidence on the outer surface of the lens. 100

I claim:

1. In a lamp having a light source, a lens provided on the side toward the light source with vertical prisms and on the side away from the light source with superimposed vertical concave flutes with vertical flats intermediate said flutes, each prism and its superimposed flute being substantially symmetrical with respect to a plane normal to the plane of the lens and connecting the apex of the prism with the center of curvature of the flute. 105

2. The lamp set forth in claim 1 in which the thickness of the lens is in such ratio to the angle of the prisms and radius of curvature 115 of the flutes that the extreme rays of the bands passing through any one prism emerge from the corresponding flute at points closely adjacent its lateral extremities and substantially no rays pass through the vertical flats. 120

In testimony whereof I affix my signature.
JOHN L. KOUBEK.
